UNITED STATES PATENT OFFICE.

WILLIAM JOHN KENNEY, OF WILMETTE, AND HENRY PHILLIP GROHN, OF CHICAGO, ILLINOIS, ASSIGNORS TO THE UNDER-FEED STOKER COMPANY OF AMERICA, OF CHICAGO, ILLINOIS, A CORPORATION OF NEW JERSEY.

AUTOMATIC STOKING APPARATUS.

1,136,679.

Specification of Letters Patent. Patented Apr. 20, 1915.

Original applications filed October 12, 1908, Serial No. 457,199, and January 29, 1912, Serial No. 673,993. Divided and this application filed January 7, 1915. Serial No. 905.

To all whom it may concern:

Be it known that we, WILLIAM J. KENNEY and HENRY P. GROHN, citizens of the United States, residing at Wilmette and Chicago, respectively, county of Cook, State of Illinois, have invented a certain new and useful Improvement in Automatic Stoking Apparatus, and declare the following to be a full, clear, and exact description of the same.

This application is a division of our prior applications Serial Nos. 457,199 and 673,993, filed, respectively, on October 12, 1908, and January 29, 1912; the first of said applications having matured into patent number 1,018,976, dated February 27, 1912.

Our invention may be said to have for its object to produce a simple and at the same time extremely flexible controlling mechanism for automatic stokers so as to regulate the feed of the fuel and the discharge of the clinkers and ashes resulting from the combustion of the fuel in the most advantageous way independently of each other; so that the fuel will be supplied in the most efficient manner under the varying conditions encountered, and the clinkers and ashes be discharged under all conditions in such a way as to secure the most efficient results.

Viewed in one of its aspects our invention may be said to have for its object to secure a proper regulation for the operating mechanisms of automatic self-cleaning stokers according to variations in the boiler pressure.

The various features of novelty whereby our invention is characterized will herein-after be pointed out with particularity in the claims; but, for a full understanding of our invention and of its objects and advantages, reference may be had to the following detailed description taken in connection with the accompanying drawings, wherein:

Figure 1 is a view partly in side elevation and partly in section of a complete automatic stoking equipment for a locomotive arranged in accordance with our invention, portions of the locomotive and its tender being indicated in dotted lines; Fig. 2 is a section taken through the fire box of the locomotive just above the stoking mechanism, showing the stoking mechanism in plan; Fig. 3 is a diagram of the piping used to

effect the automatic control of the blower and stoker mechanism, with primary controlling means associated with the throttle valve of the locomotive; and Fig. 4 is a diagrammatic plan view of the piping used to connect the several operating cylinders with the mechanism shown in Fig. 3 and with the controlling mechanism operated by the blower.

While our invention is illustrated as applied to railway locomotives and, for the sake of brevity, we shall confine the detailed description to this adaptation, we desire to have it understood that our invention is not in any way limited to railway locomotives but may be used wherever an automatic stoker is desired or required for heating boilers.

The mechanism for delivering the fuel into the furnace or fire box and for disposing of the clinkers and ashes may take any usual or preferred forms since our invention is not limited to any particular type of mechanism for this purpose. In the particular arrangement illustrated, 1 represents the fire box of a locomotive in which are placed two retorts, 2, 2. At the back end of each retort is a ram, 3, by which the fuel placed into the hopper, 4, is fed into the retort. Between the two retorts and between each of the retorts and the adjacent side wall of the fire box is a mechanism, 5, for receiving clinker and ash from the retorts and moving it forwardly toward a discharge outlet, 6, at the front end of the fire box. The discharge outlet is controlled by an oscillatory member comprising a shelf, 7, and a cutting or breaking member, 8, arranged at right angles to each other and extending across the outlet. The clinkers and ashes are fed forwardly upon the shelf 7 and, when the shelf is dropped, the portions of clinker and ash hanging over the front end of the outlet are forced down into the ash box. The members 5 and the ejector are operated from a piston mounted in a suitable cylinder, 9, and connected to the members 5 and the ejector by suitable links and levers. The retorts are arranged within a closed air chamber 10 into which air is forced and from which it passes up through suitable outlets or twyer blocks in the retorts.

In the rear end of the locomotive tender are arranged two blowers, 11, one near each side of the tender. The intake for the blowers is through the sides of the tender and the discharge is through a common flue 12, extending along the bottom of the tender to the front end thereof where it is coupled to the air chamber by a suitable flexible connection, 13. Each blower may be driven by its own engine, 14, arranged at the side thereof.

Steam is applied directly from the locomotive boiler to the blower engines, the rams and the cylinder for moving the clinkers and ashes, suitable controlling mechanism being provided to give reliable and efficient operation under all conditions.

The piping and controlling devices for the steam are best shown in Figs. 2, 3 and 4. Referring to these figures, 18 represents a pipe leading from any suitable point of the boiler and adapted to supply the requisite steam to the stoker mechanism. From this pipe extends a branch, 19, which is continued back through the tender to a point adjacent to the blower mechanism where it is connected to three automatic valve devices, 20, 21 and 22, suitably operated from one or both of the blower engines. These valve devices may be similar to those described and claimed in Patent No. 782,269 and therefore no detailed description thereof is here given. From the valve device, 20, extend two pipes, 23 and 24, which lead to the two ends of one of the ram cylinders. Similarly pipes, 25 and 26, lead from the valve device, 21, to the two ends of the other ram cylinder, and pipes, 27 and 28, lead from the valve device, 22, to the opposite ends of the cylinder, 9. Thus, whenever the blower engines are operated, steam at boiler pressure will be admitted alternately at opposite ends of the ram cylinders and of the cylinder 9 so as to reciprocate the pistons in these cylinders, the rate of reciprocation depending upon the adjustment of the valve devices, 20 to 22. Steam is supplied to the blower engines through a pipe 29 which is connected to the supply pipe 18 by means of a valve, 30. The pipe 29, like the pipe 19, extends back through the tender and is there connected to both of the blower engines. In the pipe 29 is placed a suitable regulator, 31, for the purpose of regulating the supply of steam to the blower engines. Thus when the boiler pressure is high the demand upon the stoking mechanism is only such as to maintain the pressure and is less than at times when the boiler pressure not only must be maintained but must be increased. The regulator controls the steam to the blower engines so as to make them meet the demand upon the stoking mechanism. We have not illustrated the regulator in detail since it is a common device which, as illustrated in

Patent 782,269, has heretofore been used for governing the blower engines of automatic stokers. Further control over the steam supply of the blower engines may be had by means of manually operated valves, 32 and 33, arranged on opposite sides of the regulating valve and by means of a valved by-pass, 34, extending around the regulator valve.

The main controlling valve, 30, for the steam supply to the blower engines is preferably located near the throttle valve, 35, of the locomotive and is operated by the lever, 36, of the throttle valve so that when the throttle valve is closed the valve 30 is also closed, since the demand upon the stoking mechanism ceases or is at least greatly reduced when the throttle valve of the locomotive is closed. A valved by-pass, 39, around the valve 30 permits the pipe 29 to be supplied with steam independently of the throttle valve.

It will thus be seen that the feeding of the fuel and the removal of the clinkers and ashes are independent automatic operations, each regulated by its own controller or controllers and the ultimate controlling means being the pressure of the steam in the boiler. This insures great flexibility of control and makes it possible so to operate and coördinate the various parts of the stoker mechanism as to obtain the highest efficiency under any condition that may be met.

While we have illustrated and described in detail a specific complete equipment, we of course do not desire to be limited to the various structural details so illustrated and described; but intend to cover broadly the means for controlling the engines or motors of the actuating mechanism for feeding the fuel and removing the clinkers and ashes, as will be apparent from the definitions of our invention constituting the appended claims.

We claim:

1. In combination with a boiler, a furnace, an automatic stoker in the furnace for delivering fuel thereto, apparatus for removing from the stoker the clinkers and ashes resulting from the combustion of the fuel, independent actuating means for said stoker and said apparatus, and means influenced by variations in the boiler pressure for controlling said means.
2. In combination with a boiler, a furnace, an automatic stoker in the furnace for delivering fuel thereto, a motor for actuating said stoker, apparatus for removing from the stoker the clinkers and ashes resulting from the combustion of the fuel, a second motor for actuating said apparatus, and means influenced by variations in the boiler pressure for actuating said motors.
3. In combination with a boiler, a furnace, an automatic stoker in the furnace for delivering fuel thereto, a motor for actuating

said stoker, apparatus for removing from the stoker the clinkers and ashes resulting from the combustion of the fuel, a second motor for actuating said apparatus, means influenced by variations in the boiler pressure for actuating said motors, and individual controllers for said motors.

4. In combination with a boiler, a furnace, an automatic stoker in the furnace for delivering fuel thereto, a motor for actuating said stoker, means for removing from the stoker the clinkers and ashes resulting from the combustion of the fuel, a second motor for actuating the aforesaid means, and means influenced by variations in boiler pressure for actuating said second motor.

5. In combination with a boiler, a furnace, an automatic under-feed stoker including a retort arranged within the furnace, apparatus within the furnace beside the retort for receiving clinkers and ashes therefrom and removing them, independent actuating means for said stoker and said apparatus, and means influenced by variations in the boiler pressure for controlling said actuating means.

6. In combination with a boiler, a furnace,

a retort within the furnace, means including a motor for delivering fuel to the retort, apparatus arranged in the furnace beside the retort for receiving clinkers and ashes therefrom and removing them, a second motor for actuating said apparatus, and means influenced by variations in the boiler pressure for actuating said motor.

7. In combination with a boiler, a furnace, a retort within the furnace, means including a motor for delivering fuel to the retort, means within the furnace beside the retort for receiving clinkers and ashes from the retort and removing them, a second motor for actuating the aforesaid means, means influenced by variations in boiler pressure for actuating the first motor and means influenced by variations in boiler pressure for actuating the second motor.

In testimony whereof, we sign this specification in the presence of two witnesses.

WILLIAM JOHN KENNEY.
HENRY PHILLIP GROHN.
